UNITED STATES PATENT OFFICE.

ARTHUR D. AVERY, OF LOS ANGELES, CALIFORNIA.

TYPE-WRITER ATTACHMENT.

1,106,612.

Specification of Letters Patent. Patented Aug. 11, 1914.

Application filed May 17, 1913. Serial No. 768,250.

To all whom it may concern:

Be it known that I, ARTHUR D. AVERY, a citizen of the United States, residing at Los Angeles, in the county of Los Angeles and State of California, have invented new and useful Improvements in Type-Writer Attachments, of which the following is a specification.

This invention relates to typewriter attachments, and particularly to typewriter attachments to provide a support for a roll of paper, and the principal object is to provide a typewriter attachment with a traveling roll which moves co-operatively with the carriage.

It is a further object to provide a typewriter roll carrying attachment that is readily secured to a machine of any type by a bracket and a pair of folding members.

20 In the drawings accompanying this specification and forming therewith the application for Letters Patent: Figure 1 is a rear view of a typewriter with a roll carrying apparatus attached thereto, a portion of the 25 roll being shown in section. Fig. 2 is an end view of a writing machine and of the attachment. Fig. 3 is a detail plan view of one of the carriage folding members. Fig. 4 is a detail of the severing means.

30 More specifically in the drawings, 5 designates the rear portion of the frame on which is mounted the carriage 6 having the end frames 7. Secured to the rear portion of the machine are the brackets 8 which support the rod 9 which acts as a supporting track for the roll supporting carriage 10. This carriage consists mainly of a horizontally disposed frame 11 having depending therefrom a plurality of brackets 12, pairs 35 of these brackets being adapted to form bearings for the grooved wheels 14 which rest upon the rod 9. The lower ends of these brackets are bent or formed with lugs 15 thereon which are brought together in

40 such relation that it is impossible to lift the carriage from the rail, but the interval between is sufficient to pass the brackets 8. Pivots mounted at the ends of the frame are a pair of roll supports 16, which are 45 preferably formed of sheet metal of the general channeled configuration shown, the side thereof extending beyond the connecting web adjacent the pivotal points so that the lower edge of the web rests upon the upper 50 face of the frame 11, a pivot pin being passed through a bore in the frame and the

side plates below the end of the web. These supports are locked in position by means of spring plates 18 which are secured near the ends by means of rivets 19, the members being so disposed that the pressure exerted by the spring bearing on the inclined shoulders at the ends of the frame 11 holds the support either in the vertical position shown in full lines in Fig. 1 or the open position 60 shown in dotted lines. The upper and aligned ends of these supports are provided with cylindrical studs 19 which extend on either side thereof, those facing one end forming journals for the roll 20 which is adapted 65 to be revolvably mounted thereon. The outer end of the stud is provided with an annular flange 21, the stud forming a bearing and the flange acting as a stop engaged by the slotted hooked end 22 of the pivoted brace 70 23. This hook is adapted to embrace the stud and hold the latter in fixed relation to the support for the pivot 24 of this brace, the support 25 being securely fastened to the end frame 7 of the carriage by means of fastenings 26. The roll 20 is a simple cylindrical roll preferably of wood or light metal having bores in its ends to receive the trunnions 19, these trunnions being held in resilient contact therewith by means of the 75 springs previously described. Mounted on the roll are a pair of slidable sleeves 28 which are provided with flanges 29 which face each other and are adapted to form limiting means to hold the roll of paper 30 in proper 80 relation to the roll. To lock these flanged sleeves in the proper relation thumb screws 31 are provided, which are mounted in threaded bores in a hub of the sleeve to take up against the roll 20 to secure the flanges 85 in adjustable relation.

To preserve the proper tension upon the paper roll a bearing plate 33 is provided which is hinged to a hinge plate 34 mounted centrally on the frame 11, the hinge pin 35 100 of this bearing plate having encircled therearound a coiled spring 36 whose ends are so disposed that they press this plate in resilient contact with the roll of paper 30.

From the roll of paper a sheet is carried 105 down under the platen on the carriage 6 and up in the proper position above the carriage where it is adapted to rest against a cutting plate 37 having a serrated edge 39 which is supported longitudinally on the carriage by 110 means of a pair of brackets.

The operation of the attachment will be

readily understood from the drawings and the description thereof. When it is desired to insert a roll of paper in relation to the machine the hooked braces 23 are lifted 5 from engagement with the studs 21 and a roll inserted between the studs 19 by spreading the supports 16 apart a sufficient distance to insert the latter into the roll when the braces 23 are again hooked in position, 10 the paper having been rolled upon the roll in the proper relation to the carriage and the flanges 29 secured thereto at the proper distance. The paper is now carried down under the platen on the carriage 6 and up 15 over the rest upon the plate 37, and any movement of the carriage carries the roll bearing frame 11 in the same direction along the track 9. The paper roll advances with the platen as desired in the operation of the 20 machine, and when the typing is completed the paper is pulled through until the desired point is reached and registered with the plate 37, when the paper can be severed by engaging it with this edge at this point, to 25 tear off the desired amount. When it is not desired to use the roll the braces 23 may be lifted and the roll bearing frame entirely rolled off of the rod 9 and used in another machine, there remaining only the brackets 30 8 and the braces 23, the latter of which may be folded down and not materially affect the operation or appearance of the machine.

What I claim is:

1. In a typewriter attachment in combination with a typewriting machine having a reciprocating carriage, of a rail supported adjacent thereto, a movable frame adapted to travel on said rail, a plurality of movable

supports secured to said frame, trunnions on said supports, a roll having bores adapted to receive said trunnions and a spring to press said supports into engagement with said roll.

2. In a typewriter attachment in combination with a typewriter having a movable carriage, of a track mounted adjacent and in parallel relation with the path of movement of said carriage, a frame mounted on wheels supported on said track, a plurality of resiliently mounted supports mounted on said movable frame, a roll adapted to carry a roll of paper mounted on said supports, and means to connect said roll and its supports to move with the carriage of said typewriter.

3. In a typewriter attachment in combination with a typewriter having a movable carriage thereon, a track mounted adjacent to and parallel with the path of movement of said carriage, a frame provided with wheels adapted to be supported and travel on said track, pivoted supports mounted on the ends of said frame, spring actuated means to hold said supports in rigid relation to said frame, studs mounted on said supports, flanges on said studs, and slotted hooks hinged to said movable carriage with the slots thereon adapted to embrace said flanges whereby said supports and frame may be connected to said movable carriage.

In witness that I claim the foregoing I have hereunto subscribed my name this 10th day of May, 1913.

ARTHUR D. AVERY.
